[57] **CLAIM**

The ornamental design for a combined game box with throwing and striking sticks, as shown and described.

DESCRIPTION

FIG. 1 is an exploded perspective view of a combined game box with throwing and striking sticks showing our new design;

FIG. 2 is a front elevational view of sticks and stick holding bracket; without a box;

FIG. 3 is the rear side elevational view of FIG. 2;

FIG. 4 is a left side elevational view of FIG. 2;

FIG. 5 is a right side elevational view of FIG. 2;

FIG. 6 is a top plan view of a stick holding bracket without the game box; and,

FIG. 7 is bottom plan view of FIG. 6.

The game sticks and stick holding bracket in FIGS. 2-7 are shown separately without box for clarity of illustration.
